CLEATED TRACK FOR SNOW VEHICLES

James E. Klapmeier, Mora, Minn. 55051

Filed Feb. 7, 1967, Ser. No. 6,268

Term of patent 14 years

(Cl. D14—24)

FIG. 1

FIG. 2

FIG. 3

FIG. 1 is a side elevational view of a cleated track for snow vehicles embodying my new design with a snow vehicle dotted in position for illustrative purposes only;

FIG. 2 is a sectional view thereof taken as on line 2—2 in FIG. 1;

FIG. 3 is a fragmentary top plan view thereof;

FIG. 4 is a perspective view of a portion of the top surface thereof; and

FIG. 5 is a fragmentary perspective view of the bottom surface thereof.

I claim:

The ornamental design for a cleated track for snow vehicles, as shown and described.
